ELECTRICAL CONNECTION AND BOX.

1,283,340.

Specification of Letters Patent. Patented Oct. 29, 1918.

Application filed August 7, 1914. Serial No. 855,572.

To all whom it may concern:

Be it known that we, FREDERICK F. SKEEL, a citizen of the United States, residing in Chicago, in the county of Cook and State of Illinois, and JOHN J. DOSSERT, a citizen of the United States, residing in Syracuse, in the county of Onondaga and State of New York, have invented a certain new and useful Electrical Connection and Box, of which the following is a specification.

This invention has for its object an electrical connection and box therefor, particularly applicable for use in connection with meters; and it consists in the combinations and constructions hereinafter set forth and claimed.

In describing this invention, reference is had to the accompanying drawings, in which like characters designate corresponding parts in all the views.

Figure 1 is a longitudinal sectional view partly in elevation.

Fig. 2 is an end elevation looking upwardly in Fig. 1.

Fig. 3 is an end elevation looking upwardly in Fig. 1, the entrance piece being omitted.

Figs. 4 and 5 are sectional views taken, respectively, on lines 4—4 and 5—5, Fig. 1.

Figs. 6 and 7 are, respectively, a face view and a cross-sectional view of one of the blocks of insulation of the connection, said block being shown as inverted.

Figs. 8 and 9 are views similar to Figs. 6 and 7 of the other block.

Figs. 10, 11, 12 and 13 are views similar to Figs. 6, 7, 8 and 9 of other forms of said blocks.

This electrical connection and box comprises, generally, a box having an opening in one side, an electrical connection including complementary blocks both having portions which extend into the opening of the box, and confine between them a wire passage, terminals mounted on one of the blocks within the passage, and means for holding the parts in assembled relation. It also usually includes an entrance piece common to both blocks.

1 is the box which is here shown as elongated in form and formed with an elongated opening 2 in one side thereof, the box also

having an internally threaded nipple 3 for connection with an electric conduit.

The box is also formed with extensions 18 projecting beyond the edge 6 at the open side 2 and located at the ends of the opening 2 and the box.

7 and 8 are the blocks of the connection, these blocks being formed of insulation and mounted on the open side of the box and having reduced portions 9, 10, which extend into the box 1 through the opening 2. Portions of the blocks 7, 8 also extend beyond the edge 6 at the open side of the box and are of greater dimensions than the portions 9 and 10, and hence provide shoulders 11, 12 which rest on the edge 6. The blocks 7, 8 are separable from each other along a line extending longitudinally of the opening 2 and confine a plurality of wire passages 13 between them.

14 are terminals mounted on one of the blocks 7, 8, as the block 7, within the passages 13, the terminals having binding screws at their ends, one of the binding screws of each terminal being connected to a wire within the box, and the other to a wire leading to or from the meter. The passages 13 open through the outer ends of the blocks nearer one side of the box than the other, that is, their outer ends are located on one side of a line extending centrally and lengthwise of the opening 2.

15 is an entrance piece mounted on the outer ends of both blocks 7 and 8, the entrance piece being formed with wire holes 16 located nearer one edge thereof than the other, in position to be brought into alignment with the passages 13 or out of alignment therewith when the entrance piece is reversed. The entrance piece is substantially the same in plan as a plan of the outer end face of the combined blocks 7, 8 and is formed with a marginal bead 17 on its rear side which fits into a complementary rabbet on the outer ends of the blocks 7 and 8.

18 are the extensions at opposite ends of the box which inclose the rounding end portions of the blocks 7 and 8 and the entrance piece 15. 19 is a locking bar extending transversely through the extensions 18 and engaging the outer face of the entrance piece and preferably lying in a groove 20 in

the outer face of the entrance piece, this bar serving to hold the parts in assembled relation, and when connection has been made with the terminals 14, a suitable sealing device 21 is passed through the locking bar in order that it may be readily seen if the connections have been tampered with. Means may be also provided for locking either or both of the blocks 7 and 8 in position in order that they may not be displaced when the entrance piece is removed, and as seen in Figs. 1, 2 and 3, a spring catch, such as that shown at 22, may be employed, this catch lying along the inner face of one of the extensions 18 and being fixed at one end, and having its other end free and its intermediate portion movable by its resiliency into a groove 24 in one end of the blocks 7, 8, and being movable out of the groove by pressing on the free end of the spring; or a spring catch, such as is shown at 25 may be used, which catch is located at the outer side of one of the extensions 18 and has an engaging end or pawl 26 extending through an opening in said extension in position to coact with a notch in the end of the entrance piece 15. Any suitable means may be employed to hold the blocks from displacement.

30 The passages 13, as shown in Figs. 1, 3, 4, 8 and 9, may be formed by providing ribs or barriers 27 on the block 7 on which the terminals are mounted, while the opposing face of the block 8 is plain and engages the ends or tops of the barriers. However, as seen in Figs. 10, 11, 12 and 13, the barriers, as 28, 29, may be provided on both blocks 7, 8, each block having a portion of its face plain for engaging the barriers on the other block.

In operation, the entrance piece is arranged with the holes 16 out of alinement with the passages 13 and when it is desired to make connection with the terminals 14 the bar 19 is removed, thus permitting the removal of the entrance piece and the block 8 and also the block 7, if desired, the block 7 being removed as far as the wires connected to the terminals 14 from the interior 45 of the box will permit. The entrance piece is reversed so that when it is placed in position, the holes 16 thereof will align with the passages 13. The meter wires are then passed through the holes 16 and connected to the terminals 14, the block 8 and also the block 7, if it has been displaced, replaced in the box, the entrance piece placed in position and the locking bar passed through the extensions 18 and the groove 20.

60 By means of the relative arrangement of the box the parts of the connection, the wires can be readily connected to the terminals of the connection.

What we claim is;

65 1. The combination of a box having an

opening in one side thereof, an electric connection including complementary blocks having portions extending into the box through the open side thereof, said portions closing the open side and being exposed on said open side, the blocks confining a wire passage between them, and terminals mounted on one of the blocks within the passage, substantially as and for the purpose set forth.

2. The combination of a box having an opening in one side thereof, an electric connection including complementary blocks having portions extending into the box through the open side thereof, said portions closing the open side and being exposed on said open side, the blocks confining a wire passage between them, and terminals mounted on one of the blocks within the passage, the box having extensions partly inclosing portions of the blocks, substantially as and for the purpose described.

3. The combination of a box having an opening in one side thereof, an electric connection including complementary blocks having portions extending into the box through the open side thereof, said portions closing the open side and being exposed on said open side, the blocks confining a wire passage between them and terminals mounted on one of the blocks within the passage, the box having extensions partly inclosing portions of the blocks, and means for holding the blocks from detachment, said means coacting with the extensions, substantially as and for the purpose specified.

4. The combination of a box having an elongated opening in one side thereof, an electrical connection including complementary blocks mounted on the open side of the box and having portions extending into the open side of the box, the blocks being separable by an endwise sliding movement from each other along a line extending lengthwise of said opening and confining a wire passage between them, and terminals mounted on one block on the face thereof which is opposed to the other block, and means operable from the outside of the box for normally holding the blocks from movement relatively to each other and to the box, substantially as and for the purpose described.

5. The combination of a box having an elongated opening in one side thereof, an electrical connection including complementary blocks mounted on the open side of the box and having portions extending into the open side of the box, the blocks being separable by an endwise sliding movement from each other along a line extending lengthwise of said opening, and confining a wire passage between them, and terminals mounted on one block on the face thereof which is opposed to the other block, and the box having extensions located at the ends of said opening, and lapping the ends of the blocks, and

means operable from the outside of the box for normally holding the blocks from movement relatively to each other and to the box, substantially as and for the purpose specified.

6. The combination of a box having an elongated opening in one side thereof, an electrical connection including complementary blocks mounted on the open side of the box and having portions extending into the opening of the box, the blocks being separable by an endwise sliding movement from each other along a line extending lengthwise of said opening and confining a wire passage between them, and terminals mounted on one block on the face thereof which is opposed to the other block, and the box having extensions located at the ends of said opening and lapping the ends of the blocks, and locking means associated with said extensions and coacting with the blocks to hold the same in position, substantially as and for the purpose set forth.

7. The combination of a box having an opening in one side, an electrical connection including complementary blocks extending into the box and confining a wire passage between them, the blocks being separable by a sliding movement out of the box, terminals mounted on one of the blocks in the passage, and an entrance piece mounted on both blocks and having a wire hole for alignment with the wire passage between the blocks, and means for holding the blocks and the entrance piece from movement in the box, said means being operable from the outside of the box, substantially as and for the purpose described.

8. The combination of a box having an opening in one side, and an electrical connection including complementary blocks extending into the box through the open side and confining a wire passage between them, terminals mounted on one of the blocks in the passage and an entrance piece mounted on both blocks and having a wire hole aligned with the wire passage between the blocks, and locking means operable from the outside of the box and coacting with the entrance piece and with the box to hold the blocks in the box, substantially as and for the purpose described.

9. The combination of a box having an opening in one side, an electrical connection including complementary blocks extending into the box and beyond the open side of the box, the blocks confining a wire passage between them, the blocks being separable by a sliding movement out of the box, the terminals mounted on one block and located in said passage, and an entrance piece mounted on both blocks and having a wire hole for alignment with the passage, the box having extensions on its open side inclosing portions of the blocks and the entrance piece,

and locking means coacting with the extension and the entrance piece and operable from the outside of the box, substantially as and for the purpose set forth.

10. The combination of a box having an opening in one side, an electrical connection including complementary blocks extending into the box and beyond the open side of the box, the blocks confining a wire passage between them, terminals mounted on one block and located in said passage, and an entrance piece mounted on both blocks and having a wire hole for alignment with the passage, the box having extensions on its open side inclosing portions of the blocks and the entrance piece, and locking means associated with the extensions and the entrance piece, substantially as and for the purpose described.

11. The combination of a box having an opening in one side, an electrical connection extending into the box through the open side thereof and including an entrance piece, and a locking bar extending across the entrance piece and interlocking at its ends with the box, substantially as and for the purpose set forth.

12. The combination of a box having an opening in one side, an electrical connection including complementary blocks extending into the box, terminals mounted on one of the blocks on the side thereof opposed to the other block, and an entrance piece mounted on the outer ends of both blocks and having a wire hole aligned with the passage between the blocks, and a locking bar extending through the extensions and coacting with the outer side of the entrance piece, substantially as and for the purpose described.

13. The combination of a box having an opening in one side, an electrical connection including complementary blocks extending into the box, terminals mounted on one of the blocks on the side thereof opposed to the other block, an entrance piece mounted on the outer ends of both blocks and having a wire hole aligned with the passage between the blocks, the entrance piece being formed with a groove, and a locking bar extending transversely through the extensions and lying in the groove, substantially as and for the purpose specified.

14. The combination of a box having an opening in one side, an electrical connection including complementary blocks extending into the box and beyond the open side of the box, the blocks having shoulders resting on the margin of the wall around the opening, the blocks confining a wire passage between them, terminals mounted on one of the blocks in the passage, and means for holding the blocks from detachment from the box, substantially as and for the purpose set forth.

15. The combination of a box having an

opening in one side, an electrical connection including complemental blocks extending into the box and beyond the open side of the box, the blocks having shoulders resting on the margin of the wall around the opening, the blocks confining a wire passage between them, terminals mounted on one of the blocks in the passage, the box having extensions projecting beyond the opening and in-
10 closing portions of the blocks, an entrance piece mounted on both blocks and having a wire hole for alinement with the wire passage, and means coacting with the entrance

piece for holding the same in position, substantially as and for the purpose described. 15

In testimony whereof we have hereunto signed our names, in the presence of two attesting witnesses, at Syracuse, in the county of Onondaga and State of New York, this 16th day of July, 1914.
